VANITY CASE

James L. Younghusband, Chicago, Ill.

Application October 18, 1937, Serial No. 169,571

7 Claims. (Cl. 132—79)

My invention relates to a vanity case particularly adapted for mascara and lipstick.

Among the objects of my invention is to create a vanity case adapted to hold mascara and a brush for applying the same; said vanity case so constructed as to hold two shades of mascara, such as black for conventional day use, and blue for formal or evening use; to supply a vanity case for holding both mascara and lipstick in such a manner that both may be successfully used directly from the vanity case; to provide a vanity case in which one end holds and acts as the handle end of a mascara brush, and the other end acts as a holder and applicator of lipstick and such other objects, advantages and capabilities as will later more fully appear and which are inherently possessed by my invention.

Referring to the drawing, Fig. 1 is a sectional view of one embodiment of my invention showing a vanity case with mascara and brush; Fig. 2 is a sectional view of another embodiment of my invention showing a vanity case holding mascara, brush, and lipstick; Fig. 3 is a plan view showing the vanity case with two shades of mascara; Fig. 4 is a perspective view showing the mascara brush withdrawn from the container for use; Fig. 5 is a perspective view showing the lipstick and cap withdrawn from the body of the container; and Fig. 6 is a detail view showing a preferred form of holding the mascara brush to the cap of the container.

While I have shown in the accompanying drawing preferred embodiments of my invention, yet I wish it understood that the same are susceptible of modification and change without departing from the spirit of my invention.

Referring to the embodiment illustrated in Fig. 1 my invention comprises a container 10 having side walls 11, a closed bottom 12 and an open top 13 closed by a cap 14 adapted to frictionally fit said top. Attached to the inside of walls 11 is a cake of mascara 15 having an open central portion 16 running substantially the length of the container. A brush 17 comprises a rod 18, the upper end of which is attached to the cap 14, and the lower end of which holds bristles 19. The brush 17 when not in use extends within open central portion 16 and is smaller in diameter or width so as not to contact the mascara 15. To use the brush, the user removes the cap 14 from the body of the container 10 and, using the cap 14 as a handle, rubs the brush against the mascara cake 15 on the inside of walls 11. The brush picks up the mascara and the user then may apply it to the eye lashes.

Referring to Fig. 2, my embodiment therein shown particularly provides for a container 10 having a rectangular shape providing straight walls 20. These walls are particularly adapted to hold mascara of two different shades. Ordinarily black is a preferred shade for mascara but there are times when a user desires a more daring shade such as blue for evening or formal use. Naturally the black mascara is used more often than the blue so that a container having both shades should have a greater quantity of black than blue. As particularly illustrated in Fig. 3 wherein the cake of mascara includes two shades, the black mascara 21 occupies the greater portion of the cake, and the blue mascara 22 the lesser portion. The amounts may vary so that they may be equal, or the blue mascara may be greater or less in proportion to the black in any desired degree. Because my container is preferably rectangular in shape, and the cake of mascara 15 is also rectangular, the brush may be applied to either black or blue without contact with the other shade.

Instead of the closed bottom 12 of Fig. 2, I provide as now shown in Fig. 3 another cap 23 removably attached to the body of the container 10 by friction. Attached to the inside bottom of said cap 23 is a holder 24 into which is fitted a lipstick 25. With my vanity case so fitted with lipstick the user may by removing one end use it to rouge her lips and by removing the other end use it to mascara her eye lashes. It is also within the contemplation of my invention that the holder 24 may hold eye brow pencil instead of lipstick.

The preferred form of attaching the brush 17 to the cap 14 is to cut the top of the cap 14 and bend inwardly portions 26. The top of rod 18 is placed between portions 26 and by pinching portions 26 together on rod 18, brush 17 is held in fixed position. An ornamental member 27 having a top 28 may have downwardly extending portions 29 adapted to fit between portions 26 and rod 18 so as to hold brush 17 in fixed position.

While I have shown two shades of mascara in Fig. 3, yet it is within the spirit of my invention that a plurality of shades may be used. My square container is particularly adaptable to three or even four shades of mascara, so that conceivably my vanity case would hold black, brown, blue and green mascara. The square container permits a user to contact one shade without danger of contacting any other shade because the walls are straight and defined.

Having thus described my invention, I claim:

1. A vanity case comprising a rectangular container having an open top, the inner walls of said container having one shade of mascara on one side and another shade of mascara on another side, said mascara leaving a central bore, a removable cap for the open top of said container, and a brush attached to said cap, said brush being of smaller cross section than said central bore, said brush extending into said central bore so as to be free from accidental contact with the walls of the container; said brush adapted upon removal of the cap from the container to enter the open top of the container and to contact and pick up thereon the shade and exact amount of mascara from the inner walls as desired by the user.

2. A vanity case comprising a container having open ends, the inner walls of said container having mascara attached thereto, a removable cap on each end of said container, one of said caps having a brush extending into said container and the other cap holding a lipstick; said brush adapted upon removal of the cap from the container to enter the open end of the container and to contact and pick up thereon the mascara from the inner walls as desired by the user.

3. A vanity case comprising a container having an open top, the inner walls of said container having mascara attached thereto, a removable cap on each end of said container, one of said caps having a brush extending into said container and the other cap holding an eyebrow pencil, said brush adapted upon removal of the cap from the container to enter the open end of the container and to contact and pick up thereon the mascara from the inner walls as desired by the user.

4. A vanity case comprising a container having an open top, mascara coated on the inner walls of said container and leaving a central bore, a removable cap for the open top of said container, the top of said cap cut at the center to form downwardly extending portions, a brush having a rod, the upper end of said rod held between said downwardly extending portions, said brush having bristles at its lower portion extending into said central bore, said brush being smaller in cross section than said bore so that the bristles of said brush do not accidentally touch and pick up an undesired amount of mascara from the inner walls; said brush adapted upon removal of the cap from the container to enter the open top of the container and to contact and pick up thereon the small and exact amount of mascara from the inner walls as desired by the user.

5. A vanity case comprising a container having an open top, mascara attached to the inner walls of said container and having a central bore, a removable cap for the open top of said container, the top of said cap cut at the center to form downwardly extending portions, an ornamental member having a top portion for covering the cut part of the top of said cap, and having lower extensions, extending between said downward extending portions, a brush having a rod, the upper end of said rod held between said extensions, said brush having bristles at its lower portion extending into said central bore, said brush being smaller in cross section than said bore so that the bristles of said brush do not accidentally touch and pick up an undesired amount of mascara from the inner walls; said brush adapted upon removal of the cap from the container to enter the open top of the container and to contact and pick up thereon the small and exact amount of the mascara from the inner walls as desired by the user.

6. A vanity case comprising a container having an open top, a plurality of shades of mascara attached to different portions of the inner walls of said container, said mascara having a central bore, a removable cap for the open top of said container, and a brush attached to said cap, said brush being of smaller cross section than said central bore, said brush extending into said central bore so as to be free from accidental contact with the walls of the container; said brush adapted upon removal of the cap from the container to enter the open top of the container and to contact and pick up thereon the shade and exact amount of mascara from the inner walls as desired by the user.

7. A vanity case comprising a container having an open top, a cake of cosmetic material attached to the inner walls of said container and having a hollow portion, a removable cap for the open top of said container, and a brush attached to said cap, said brush being smaller in cross section than the lateral extent of said hollow portion so that said brush when not in use extends into said hollow portion without touching and picking up any of the cosmetic material on the walls of the container, said brush adapted upon removal of the cap from the container to enter the open end of the container and to contact and pick up thereon the correct and small amount of mascara from the inner walls desired by the user.

JAMES L. YOUNGHUSBAND.
